His Attorney.

UNITED STATES PATENT OFFICE

KONRAD RUPPRECHT, OF BERLIN, GERMANY, ASSIGNOR TO GENERAL ELECTRIC COMPANY, A CORPORATION OF NEW YORK

AUTOMATIC GRINDER CONTROL

Application filed May 13, 1927, Serial No. 191,244, and in Germany June 8, 1926.

It is already known how to regulate the pressure on the wood when several grinders are driven by a common electromotor, so that the grinder motor is constantly loaded and the pressures on the several grinders are substantially equal. In this case the constant load of the grinder motor is maintained in all circumstances, for example, even when one of the grinders or when one of the feed devices is put out of operation. In such a case the pressure on the stone remaining in operation is increased to such an extent that the grinder motor remains normally loaded. In this connection, however, there is the disadvantage that the grinding is too coarse and thus difficulties may occur in the further working of the pulp.

In order to obtain a grinding of constantly equal value, the grinder drive according to the invention is to have such a regulating device that on the failure of one grinder or its feed mechanism, the pressure on the stone of the grinder still in operation remains unchanged. Naturally in this case an overloading of the grinder motor must be taken into account.

This regulating device can now be constructed in so simple a manner that on the stopping of the grinder or when the feed arrangement is cut out of operation, the stones are automatically unloaded and the feed motors are only again switched in when the grinding operation is resumed. In this manner the stones are spared. At the same time the advantage is afforded that the starting of the grinder motor is facilitated and the starting current strength is reduced, so that fewer requirements are made in respect to the construction of the grinder motors. This is of special importance for the use of asynchronously starting synchronous motors whose construction requires different designs according to the value of the starting moment desired. If the drive of the wood feed arrangements is effected through a chain gear, as will be mostly the case in practice, then the unloading of the grinders cannot be effected by the running back of the feed motors, because the chain transmission is only arranged for a definite working direction. An effective

unloading can therefore only be made by raising the magazine of the grinder.

A constructional example of the subject of the application is represented in the accompanying drawing. M designates the grinder motor which is coupled with two grind stones which are not represented. The feed motors M_1 and M_2 , which are constructed as single phase alternating current commutator motors, for example, as repulsion-motors, serve for the drive of the wood feed arrangements. The lifting motors M_3 and M_4 serve for lowering and raising the magazines for the wood being ground. These motors are suitably arranged as three-phase asynchronous motors with short-circuit rotor. They can also be three-phase or direct current motors without the effect of the lifting arrangements being impaired. The commutator motors M_1 and M_2 are connected in parallel and are fed in common by two single-phase transformers located in the line of the grinder motor—a voltage transformer T_1 and a current transformer T_2 —in well known differential connection through the circuit controllers or contactors S_1 and S_2 . The number of secondary windings of the transformer T_2 can be varied in dependence on the number of grinders in operation, so that the secondary voltage of this transformer can be maintained at the same value independently of the number of grinders actually in operation. This is only possible when on switching in only one feed motor the effective number of ampere turns is the same as in the case of operation with both feed motors. For this purpose the transformer T_2 must have such a number of turns that also in the case of only one grinder operating, the counter voltage and also the voltage supplied to the connected feed motor maintain their normal value. The transformer T_2 can also be set up with the normal number of turns for operating both grinders and when operating only one grinder a booster transformer T_2' can be connected in series with transformer T_2 . The effect of the current transformer T_2 , T_2' is more complete if a choke coil D , D' is connected in parallel. It is suitable to provide

the transformers T_2 , T_2' as well as the choke coils D , D' with taps.

In order to vary the effective number of turns of the transformers T_2 , T_2' in the manner required when changing over from operation with one feed motor to that with two feed motors or vice versa, the protective devices S_1 and S_2 are provided with corresponding contacts. If, for example, both feed motors are operated then their circuit is closed through the main contacts 10 and 11 of the contactors S_2 and S_1 , through the predetermined portion of the secondary of transformer T_2 , through the winding of the feed motor M_1 through the main contact 12 of the contactor S_1 and the secondary winding of the transformer T_1 . The other feed motor winding is similarly energized through the main contact 13 of contactor S_2 . If only one of the feed motors is to be operated then the other is cut out by opening the associated control switch H_1 or H_2 . If, for example, feed motor M_2 is cut out, then the circuit of the feed motor M_1 working alone is as follows: Main contact 14 of contactor S_1 and contact 15 of contactor S_2 , connections 16-17 of the transformer windings T_2' and T_2 , windings of the feed motor M_1 , main contact 12 of contactor S_1 and the secondary winding of the transformer T_1 . If protective device S_1 is cut out and S_2 only is closed then the course of the circuit of feed motor M_2 is through a similar circuit which is readily traced.

The automatic change over switches or contactors U and U' for the lifting motors M_3 and M_4 , according to the invention, are interconnected with the contactors S_1 and S_2 of the feed motors in such a manner that the contactor S_1 must be in its open position, that shown, in order for the contactor U to be energized and closed to energize the lifting motor M_3 in the lifting direction. This is accomplished by the auxiliary switch 18 associated with contactor S_1 which is closed only when contactor S_1 is in its open position. The upper limit switch of magazine No. 1 automatically opens when magazine No. 1 is raised to its predetermined upper limit, and thus deenergizes the motor M_3 . Also, the magazine No. 1 must be in its predetermined lower position before the feed motor M_1 can be energized to feed the wood to the stone associated with this magazine. This is controlled by the right hand contact of the lower limit switch of magazine No. 1 which is closed only when the magazine has been lowered to the predetermined position. This lower limit switch automatically deenergizes motor M_3 to stop the lowering of the magazine at the predetermined position. A similar arrangement is provided for the control of the feed motor M_2 and the magazine lifting and lowering motor M_4 . On the other hand the feed motors cannot be switched in before the press boxes are again lowered. The push

buttons E and E' serve respectively to control the lifting and lowering motors M_3 and M_4 for lowering the associated magazines. If either of these buttons is pressed for a short time then the corresponding contactor U or U' is closed for "lowering" and remains closed until the associated lower limit switch is opened. It is assumed that the oil switch O has been previously closed and the grinder motor M has been started, so that the control current interlocking contacts 19 at the oil switch and similar contacts 20 of the starter A are closed. It is also assumed that the disconnecting switches 21 and 22 of motors M_3 and M_4 are closed.

In the operation of the system as heretofore described, the disconnecting switches 21 and 22 for the motors M_3 and M_4 are closed whereby the control of these motors can be effected through their respective contactors U and U' . These motors are then started up by means of the push buttons E and E' respectively and operate in a direction to lower the magazines, the motors being stopped with the magazines in their lowermost positions by means of the lower limit switches.

The grinder motor M is now started by closing the oil switch O which also closes the interlocked contacts 19 in the operating coil circuits for the contactors S_1 and S_2 . The grinder motor M is accelerated to full speed by moving the starting device A to short circuit the resistance in the secondary circuit of the grinder motor, and when the resistance has been short circuited the starting device closes a circuit between the contacts 20 which completes the circuit for the operating coils of the contactors S_1 and S_2 through the right hand contacts of the lower limit switches of the two magazines, which contacts were closed when the magazines were lowered. The closing of the contactors S_1 and S_2 start the feed motors M_1 and M_2 which operate to feed the wood to the grinder stones.

By opening the manually operated switches H_1 and H_2 either one of the contactors S_1 and S_2 can be opened to deenergize the respective feed motor. When this occurs the corresponding magazine motor M_3 or M_4 is automatically started up in a direction to lift the magazine. This is effected by means of the auxiliary switch 18 connected with each of the contactors S_1 and S_2 , which switch is closed when the contactor opens thereby operating the corresponding magazine motor contactor U or U' in a direction to cause the motor to raise the magazine. When the magazine has been raised to its uppermost position the motor is stopped by the limit switch associated with the magazine. With this arrangement it will be observed that when either one of the feed motors is deenergized the corresponding magazine is au-

tomatically lifted to remove all loads from the corresponding stone.

The raising of the magazine opens the right hand contact of its lower limit switch 5 which in turn opens the circuit for the operating coil for the contactor S_1 or S_2 of the feed motor, thus preventing the restarting of the feed motor until the magazine has been first lowered by pressing the appropriate 10 button E or E'. When the button is pressed to again lower the magazine with the grinder motor operating, the corresponding feed motor is automatically restarted by the closing of the right hand contacts of the lower limit 15 switch of the magazine.

The following advantages are obtained through this mutual interlocking and automatic connection:

(1) All switching processes take place in 20 the right order.

(2) The grinder motor on starting is only loaded with the stones running light.

(3) The connecting of the feed motor is only positively and automatically effected after 25 the lowering of the associated magazines.

(4) The connection of the current transformer T_2 corresponds to the actual operating condition of the grinders.

(5) On switching off the feed motors the 30 magazines are automatically lifted.

(6) On releasing the oil switch O the feed motors are automatically disconnected and the grinders are unloaded.

When work is to be done by only one of 35 the two grinders, then the feed motor and the lifting motor of the other grinder can be cut out by means of the switches H_1 and H_3 or H_2 and H_4 .

The arrangement described above can also 40 be used for installations in which the grinder motor M drives more than two or only one grind stone. The arrangement is also easily adaptable for the case where the grinder has several magazines which are fed by a corresponding number of feed motors.

What I claim as new and desire to secure by Letters Patent of the United States, is:

1. In combination, in a system of control for a grinder, a motor for operating feed 50 mechanism for the grinder, a second motor for raising the grinder magazine, and electrical connections through which said second motor is automatically energized to raise the magazine when said feed motor is deener- 55 gized.

2. In combination in a system of control for a grinder, a motor for operating feed mechanism for the grinder, a second motor for raising and lowering the grinder maga- 60 zine, and electrical connections through which said second motor is automatically deener- gized and said feed motor is automatically energized when the magazine has been lowered to a predetermined position.

65 3. In combination in a system of control

for a grinder, a motor for operating feed mechanism for the grinder, a second motor for raising and lowering the grinder magazine, controlling means for said motors, and electrical connections through which said second motor is automatically energized to raise the magazine when said feed motor is deenergized, and said second motor is automatically deenergized and said feed motor is automatically energized when the magazine has been lowered to a predetermined position. 70

4. In combination in a system of control for a plural stone grinder, a grinder motor for operating the grind stones, a separate motor for operating an associated feed mechanism for each of said stones, switching mechanism for selectively controlling the energization of said motors, an automatic regulator for regulating the operation of said feed motors in dependence on the load on said grinder motor, and means for automatically adjusting the said regulator in dependence on the number of said feed motors in operation. 75

5. In combination in a system of control for a plural stone grinder, a grinder motor for operating the grind stones, a separate motor for operating an associated feed mechanism for each of said stones, switching mechanism for selectively controlling the energization of said motors, means responsive to the current supplied to said grinder motor for regulating the operation of said feed motor, and means operated by said switching mechanism for adjusting said regulating means in dependence on the number of said feed motors in operation. 90

In witness whereof, I have hereunto set my hand this 25th day of April, 1927. 95
